DRAG-LINE BUCKET

Application filed December 20, 1926. Serial No. 155,785.

This invention relates to an improvement in dragline buckets of the type wherein the hauling line or dragline is connected to the forward ends of the sides of the bucket and the hoisting line is connected to the sides of the bucket intermediate the forward and rearward ends thereof.

Heretofore in the art, with this type of bucket, the sides had a tendency to, and 10 frequently were, bent or pulled toward each other due to the strains imposed thereon by the dragline and hoisting line. Such a distortion of the bucket is undesirable for several reasons, the principal disadvantages 15 being that the capacity of the bucket is reduced, its ability to fill and to unload quickly impaired and its strength and durability diminished.

One of the principal objects of the present 20 invention is to provide a bucket of this type which may be conveniently and easily constructed from sheet metal of ordinary weight and thickness and yet is so braced and strengthened as to maintain its form and resist distortion even when subjected to the 25 severe stresses imposed thereon by the dragline and the hoist line during the operation of the bucket.

In carrying out the present invention, the 30 dragline bucket comprises a bucket body which may be constructed of a single piece of metal shaped and folded to provide a bottom, a pair of sides and a back, the adjacent edges of the sides and back contacting 35 and being welded together. If desirable, the bucket body may be constructed of two pieces of metal, one piece being shaped and folded to provide the bottom and sides and the other piece being shaped to constitute the back. When the bucket body is 40 constructed of two pieces of metal, the side edges of the back are welded to the rear edges of the sides as in the single piece bucket and, in addition, the lower edge of 45 the back is welded to the rear edge of the bottom.

The bucket body so constructed is strengthened, stiffened and braced by means of a tubular or box section bridge having an 50 arched portion overlying the bucket body

and having depending portions or extensions flatly engaging the sides and welded thereto. The tubular, box-like form of the bracing bridge is preferably attained by building up the bridge of a bottom plate, 55 a top plate and Z-bars interposed between the top plate and the bottom plate and welded thereto.

The bucket is further strengthened, stiffened and braced by means of longitudinal 60 bracing members welded to the side plates and overlapping and welded to the end portions of the bridge. The upper edges of the bucket body not overlapped by the bridge are strengthened, stiffened and 65 braced by bracing strips extending along and welded thereto.

Cutting or digging means is provided on the bucket and is mounted thereon in novel manner.

Other objects and advantages reside in certain novel features of the construction, arrangement and combination of parts which will be hereinafter more fully described and particularly pointed out in the 75 appended claims, reference being had to the accompanying drawings forming a part of this specification, and in which:

Figure 1 is a view in front elevation showing a bucket embodying the present invention;

Figure 2 is a view thereof in side elevation;

Figure 3 is a plan view showing the blank from which the bucket body is developed;

Figure 4 is a fragmentary view in transverse section on line 4-4 of Figure 1;

Figure 5 is a fragmentary view in vertical section on line 5-5 of Figure 2;

Figure 6 is a fragmentary view in horizontal section on line 6-6 of Figure 2; and

Figure 7 is a fragmentary vertical sectional view on line 7-7 of Figure 1.

Referring to the drawings, it will be seen that the dragline bucket embodying the present invention comprises a bucket body which may be constructed of a single piece of sheet steel cut out and shaped as shown in Figure 3 and bent or folded along lines *a*, *b* and *c* to provide a bottom plate 1, sides plates 2, 95 100

and a back plate 3. The curved rear edges of the side plates 2 contact with the curved side edges of back plate 3 and are welded thereto. If desirable, the back plate 3 may be made of a separate piece of metal and in such event not only are its curved side edges welded to the rear edges of the side plates, but its lower edge is welded to the rear edge of the bottom plate.

10 For the purpose of stiffening, strengthening and bracing the bucket body, a tubular or box-like bracing bridge, designated generally at 5, is provided and has an arched portion 6 overlying the bucket body and depending portions 7 extending down along

15 the outside of and secured to the side plates of the bucket body at the forward ends thereof. The bridge 5 is built up of a bottom plate 8, a top plate 9, and Z-bars 10.

20 The end portions of the bottom plate 8 flatly engage the outer surfaces of the forward end portions of the side plates of the bucket, but above the bucket body this bottom plate 8 is curved or arched, as shown in the drawings. The top plate 9 for the major portion of its extent is disposed above and in spaced relation to the bottom plate 8 and between the plates 8 and 9 the Z-bars 10 are interposed. As shown, the top plate 9 is of

25 slightly less width and also of less length than the bottom plate 8, the top plate 9 engaging and being welded to the upper flanges 10^a of the Z-bars, while the bottom plate 8 engages and is welded to the lower flanges 10^b thereof. The Z-bars 10 terminate

30 above the lower ends of the bottom plate 8 and have the flanges 10^a and the body portions thereof cut away. The top plate 9 is bent in around the cutaway ends of the Z-

35 bars and has its extremities bearing against and welded to the outer faces of the end portions of the bottom plate. In this way a tubular or box-like bracing bridge of light weight, but of great strength and stiffness, is provided. This tubular bracing bridge

40 rigidly maintains the side walls of the bucket in spaced relation and prevents distortion or collapsing of the side walls without adding materially to the weight of the bucket.

45 It is to be noted that the ends of the bottom plate 8 of the bridge are enlarged as indicated at 8^a and these enlarged ends are welded to the side plates of the bucket. Thus the bridge distributes its bracing, strengthening and stiffening action over a relatively large area of the side plates of the bucket.

50 The body of the bucket is further strengthened, braced and stiffened by means of longitudinally extending, bracing or reinforcing members 15, the members 15 preferably taking the form of plates which flatly engage and are welded to the end portions 8^a of the bottom plate 8 of the bridge and which also flatly engage and are welded to filler pieces 16, the filler pieces, in turn, being

welded to the side plates of the bucket. The reinforcing and bracing plates 15 are themselves stiffened and strengthened by pressing out portions thereof, as indicated at 15^a.

70 The end portions 8^a of the bottom plate of the bridge overlap considerable portions of the upper edges of the side plates of the bucket body and the portions of such edges not overlapped in this manner are reinforced, strengthened and stiffened by strips 20 extending around the outside of such edges and around the outside of the upper edge of the back plate and welded to such edges.

75 Cutting or digging means is provided on the bucket and consists of a plurality of excavating teeth 25 mounted on the bottom plate 1 and on a mounting bar 26. The mounting bar 26 has attached portions 27^a 80 suitably secured to the side plates of the bucket and it has a main portion 27 extending around and snugly engaging the outer side of the bottom of the bucket adjacent the forward edge thereof. This main portion 27 of the bar projects beyond the front edge of the bottom plate of the bucket. Each excavating tooth 25 has its rear portion formed with a slot 28 defining an upper attaching section 29 and a lower attaching section 30 85 on each tooth. The slot 28 is of different widths, so that the upper attaching section 29 flatly engages the upper surface of the projecting end of the bar 26 for a portion of its extent and flatly engages the upper surface of the bottom of the bucket for a portion of its extent. The lower section 30 engages the under surface of the body portion 27 of the bar 26 throughout its extent. Fastening devices 31 secure both sections of 90 the tooth 25 to the projecting portion of the bar, fastening devices 32 secure both sections of the tooth to the bar 26 and to the bottom plate 1 and fastening devices 33 secure the lower section of the tooth to the 95 bottom plate and to the bar.

100 Clevises 40 are connected with the forward ends of the bucket at the portions reinforced by the bridge and by the reinforcing plates 15. Hoist line attachment devices 41 105 are also provided on the bucket sides.

110 Attaching angles 50 are mounted on the crest of the arched portion 6 of the bridge 5 and are suitably welded in position. The forward end portions of these attaching angles 50 extend over and are welded to a U-shaped supporting member 51 welded to the underlying portion of the Z-bar 10.

115 With this bucket construction the bucket may be made comparatively light in weight 120 and is properly balanced so as to be easily controlled and operated. Along with these advantages it is possible to construct the bucket body of a single piece of metal or two pieces of metal, if the latter be desired. 125

And yet with this light weight, well balanced construction the bucket may not be and will not be distorted or collapsed because the sides of the bucket are rigidly maintained in proper position and are strengthened, braced and stiffened in the main by the tubular or box-like bridge and also by other novel reinforcing means, that is, by the reinforcing strips 15 and 20. The bucket can also be made smooth on the inside to prevent dirt from sticking thereon.

The invention claimed is:

1. An excavating bucket comprising a bucket body having side walls and a tubular bracing bridge extending above and between the side walls and positively and rigidly connected thereto, said tubular bracing bridge being made up of spaced plates and connecting pieces extending between and secured to said plates. 70
2. An excavating bucket comprising a bucket body having side walls and a tubular bracing bridge including an arched portion extending over the body of the bucket and between the side walls thereof and also including downwardly extending portions at its ends, said downwardly extending portions being disposed along the outside of the side walls, said bridge being made up of a bottom plate, the lower ends of which are rigidly and securely fastened to the side walls, a top plate, and bars disposed between and secured to the top and bottom plates. 75
3. An excavating bucket comprising a bucket body having side walls and a tubular bracing bridge including an arched portion extending over the body of the bucket and between the side walls thereof and also including downwardly extending portions at its ends, said downwardly extending portions being disposed along the outside of the side walls, said bridge being made up of a bottom plate, the lower ends of which are rigidly and securely fastened to the side walls, a top plate, and bars disposed between and secured to the top and bottom plates. 80
4. An excavating bucket comprising a bucket body having side walls and a tubular bracing bridge including a portion extending over the body of the bucket and between the side walls thereof and also including downwardly extending portions at its ends, said downwardly extending portions being disposed adjacent the side walls, said bridge being made up of a bottom plate, the lower ends of which are rigidly and securely fastened to the side walls, a top plate, and connecting pieces disposed between and welded to the top and bottom plates. 85
5. An excavating bucket comprising a bucket body having side walls and a tubular bracing bridge including an arched portion extending over the body of the bucket and between the side walls thereof and also including downwardly extending portions at its ends, said downwardly extending portions being disposed along the outside of the side walls, said bridge being made up of a bottom plate, the lower ends of which are rigidly and securely fastened to the side walls, a top plate, and Z-bars disposed between and secured to the top and bottom plates. 90
6. An excavating bucket comprising a bucket body having side walls and a tubular bracing bridge including an arched portion extending over the body of the bucket and between the side walls thereof and also including downwardly extending portions at its ends, said downwardly extending portions being disposed along the outside of the side walls, said bridge being made up of a bottom plate, the lower ends of which are rigidly and securely fastened to the side walls, a top plate, and Z-bars disposed between and secured to the top and bottom plates, said top plate and said Z-bars terminating short of the lower ends of the bottom plate to leave a flat portion thereof exposed to facilitate attachment of the tubular bridge to the side plates of the bucket body. 95
7. An excavating bucket body having a tubular, box-like bracing bridge extending between and secured to spaced walls thereof. 100
8. An excavating bucket comprising a bucket body having side walls, and a tubular, box-like bracing bridge extending between and above the side walls, said bridge having an arched portion overlying the bucket body and end portions secured to the side walls. 105
9. An excavating bucket comprising a bucket body having side walls and a tubular bracing bridge including an arched portion extending over the body of the bucket and between the side walls thereof and also including downwardly extending portions being disposed along the outside of the side walls, said bridge being made up of a bottom plate having its lower ends welded to the side walls, a top plate, and Z-bars disposed between and welded to the top and bottom plates, said top plate and said Z-bars terminating short of the lower ends of the bottom plate to leave a flat portion thereof exposed, and reinforcing means welded to the bucket and to the exposed portion of said bottom plate. 110
10. An excavating bucket comprising a bucket body having side walls and a tubular bracing bridge including an arched por- 115
11. An excavating bucket comprising a bucket body having side walls and a tubular bracing bridge including an arched portion extending over the body of the bucket and between the side walls thereof and also including downwardly extending portions being disposed along the outside of the side walls, said bridge being made up of a bottom plate having its lower ends welded to the side walls, a top plate, and Z-bars disposed between and welded to the top and bottom plates, said top plate and said Z-bars terminating short of the lower ends of the bottom plate to leave a flat portion thereof exposed, and reinforcing means welded to the bucket and to the exposed portion of said bottom plate. 120
12. An excavating bucket comprising a bucket body having side walls and a tubular bracing bridge including an arched por- 125
13. An excavating bucket comprising a bucket body having side walls and a tubular bracing bridge including an arched por- 130

tion extending over the body of the bucket and between the side walls thereof and also including downwardly extending portions being disposed along the outside of the side walls, said bridge being made up of a bottom plate having its lower ends welded to the side walls, a top plate, and Z-bars disposed between and welded to the top and bottom plates.

10 11. An excavating bucket comprising a bucket body having side walls and a tubular, boxlike, bracing bridge having an arched portion extending above and between said side walls and having downwardly ex-

15 tending portions overlapping and secured to said side walls, said bridge being made up of spaced plates and connecting pieces disposed between and secured to said plates.

12. An excavating bucket having side 20 plates, a tubular bracing bridge made up of spaced plates and connecting pieces extending between and secured to said spaced plates, one of said plates having lower portions fitting flatly against and extending 25 over a large area of the side plates and means for securing said lower portions to said side plates.

13. An excavating bucket having side plates, a tubular bracing bridge made up of spaced 30 plates and connecting pieces extending between and secured to said spaced plates, one of said plates having lower portions extending over a large area of the side plates, means for securing said lower portions to 35 said side plates, and reinforcing members secured to said lower portions and extending along and secured to said side plates.

In witness whereof, I hereto affix my signature.

40 HOLGER L. MITCHELL.
